UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR CRACKING OIL.

Application filed December 9, 1920. Serial No. 429,306.

To all whom it may concern:

Be it known that I, CARBON P. DUBBS, a citizen of the United States, residing in the city of Wilmette, county of Cook, and State 5 of Illinois, have invented certain new and useful Improvements in Processes for Cracking Oil, of which the following is a specification.

This invention relates to improvements in 10 processes for cracking oil and refers more particularly to the manner of handling the carbon containing residue which is one of the principal problems in the commercial operation of the cracking process.

15 In the present invention, the oil, preferably in liquid phase, is delivered to an expansion or vapor chamber where vaporization takes place and the oil and the carbon is precipitated. I have alternate expansion 20 chambers for receiving the carbon, one of which may be cleaned while the other is in use. It is highly desirable, however, that when one of the chambers is cut into the system, that it be cut in at the desired operating pressure and that the vapor chamber be not too cold. The present invention 25 is also directed to the method and means of accomplishing this.

In the drawing, the single figure represents 30 a somewhat diagrammatic view, partly in side elevation and partly in vertical section, of my improved apparatus.

Referring particularly to the drawing, 1 designates the furnace having burner 2, bridge wall 3, stack 4 and combustion chamber 5. In the combustion chamber is mounted 35 the heating element or chamber 6 which may take the form of a 3" to 6" continuous coil of pipe. Oil is supplied to the inlet end of this coil through feed line 7 having throttle valve 8 connected to the discharge side of pump 9. The inlet side of the pump is connected by pipe 10 having throttle valve 40 having any suitable source of raw oil supply.

45 The discharge end of the coil is connected to transfer line 12 having throttle valve 13. This transfer line 12 has one branch 14 having throttle valve 15 leading to expansion chamber 16. It also has a second 50 branch 17 having throttle valve 18 leading to vertical expansion chamber 19. Each expansion chamber is provided with the liquid residue drawoff pipe 20 controlled by throttle valve 21 and may be independently heated by means of the burners 22.

Means are provided for introducing raw oil to the expansion chamber through pipes 23 controlled by valves 24, the pipes 23 being suitably connected to a pressure pump for forcing oil under pressure into the vapor 60 chambers. This oil, introduced through the pipes 23, is used only to raise a vapor chamber initially to desired pressure, before it is cut into the system and while the other one is being cleaned. The oil so introduced 65 is gradually withdrawn through the pipes 20 as soon as the vapor chamber in question is open to the heating coil. The oil should be withdrawn in such a way as to prevent the pressure on the system dropping below 70 that required. The oil so drawn out through the pipe 20 may be conveyed to a suitable receptacle and if desired, reused for the same purpose, the carbon containing residue, as the process proceeds, should be withdrawn 75 out of the vapor chamber in use to a suitable residuum tank.

The top of each vapor chamber is provided with a vapor outlet pipe 25 having throttle valves 26 and 27 respectively. The pipes 25 connect to a header 28, which has a vapor pipe 29 leading to the lower side of dephlegmator 30. This dephlegmator 30 is provided with suitable comminuted baffling material 31. The upper end of the dephlegmator is provided with vapor pipe having throttle valve 33 and connected to the upper end of condenser coil 34 seated in condenser box 35. The lower end of the coil is connected to the top of receiver 36, which receiver has liquid level gauge 37, liquid drawoff pipe 38, controlled by throttle valve 39 and gas outlet pipe 40 controlled by throttle valve 41. The system is provided with suitable pressure gauges 42 as shown. The reflux condensate is drawn from the bottom 90 of the dephlegmator through pipe 43 having throttle valve 44 leading to the suction side of the pump 9.

The process may be operated as follows: 100 Oil, as for example, heavy fuel oil or asphaltic base crudes, may be fed continuously through the heating coil and heated to a temperature of say, 650 degrees F. to 850 degrees F. at a pressure of from 100 pounds to 300 pounds. Care should be taken to keep the oil substantially in liquid phase as it is delivered to the vapor chamber. Assuming that the vapor chamber 16 is first used, the vapor chamber 19 will be cut out 105 110

of the system by closing the valves 18 and 27, the valves 15 and 26 being open. As vaporization takes place, in the chamber 16, the vapors will pass out into the dephlegmator where the heavier ones will be condensed and continuously returned to the system for further treatment. The lighter vapors will be passed to the water condenser and thence to the receiver. A uniform pressure may 10 be maintained on the entire system.

If desired, a differential pressure may be maintained on the system, as for example, a lesser pressure on the vapor chamber than the heating coil, by suitably regulating the 15 valves 13 and 15 and the valves on the vapor outlets of the vapor chambers. As the process proceeds, carbon will accumulate in the chamber 16 even though the residue is drawn off, until eventually it will be 20 necessary to clean the chamber 16. Meantime, the heating tubes will be substantially free from carbon and can be operated for a much longer period than the vapor chamber without cleaning. Before attempting to cut 25 the vapor chamber 16 out of the system, the chamber 19 is filled with oil by means of the pump connected to the pipe 23 leading to the vapor chamber 19. The burner 22 under chamber 19 may be lit and the oil heated 30 so that the vapor chamber will not be cold. The vapor chamber may, if desired, be heated to the same temperature as the other one and maintained under an expanded liquid pressure by means of heating the oil 35 and by means of the supply pump connected to the pipe pump 23. When the vapor chamber has reached the desired pressure and temperature, it being understood that the entire system is plentifully supplied with 40 thermometers to determine pressure and temperature, the valves 15 and 26 are closed and the valves 18 and 27 opened. The chamber 19 now serves as the expansion chamber instead of the chamber 16 and the latter may 45 be cleaned and put in condition to operate when the chamber 19 may need cleaning. By this method, the process may be operated very smoothly and without any stress on the apparatus and in fact the vapor chambers 50 may be interchanged without any fluctuation in temperature or pressure on the rest of the apparatus. Nicety of control of temperature and pressure are frequently desirable in cracking processes and this is 55 accomplished by means of my process. As far as I am aware the apparatus here shown is also novel and patentable.

I claim as my invention:

1. A process of cracking oil, consisting in 60 heating the oil in the heating coil, passing it thence to one of a plurality of vapor chambers where vaporization and carbon precipitation takes place, periodically cutting this vapor chamber out of the system for 65 cleaning and simultaneously cutting a sec-

ond vapor chamber into the system, said latter vapor chamber at the time it is cut into the system being maintained under a predetermined oil pressure and temperature, substantially equal to the pressure and temperature of the first chamber at the time it was cut out of the system by externally heating a body of oil in said latter vapor chamber. 70

2. A process of cracking oil, consisting in 75 heating the oil in a heating coil, passing it thence to one of a plurality of vapor chambers where vaporization and carbon precipitation takes place, periodically cutting this vapor chamber out of the system for cleaning and simultaneously cutting a second vapor chamber into the system, said latter vapor chamber at the time it is cut into the system being maintained under a predetermined oil pressure and temperature by externally heating a body of oil in said latter vapor chamber. 80

3. A process of cracking oil consisting in 85 heating the oil in a heating coil, passing it thence to one of a plurality of vapor chambers where vaporization and carbon precipitation takes place, periodically cutting this vapor chamber out of the system for cleaning and simultaneously cutting a second vapor chamber into the system, introducing 90 a body of oil into the latter vapor chamber previously to the time it is cut into the system and maintaining said latter chamber under a predetermined oil pressure and temperature equal to the pressure and temperature of the first chamber at the time it was cut out of the system by externally heating said body of oil in said latter vapor chamber. 95

4. A process of cracking oil consisting in 100 heating a stream of oil to a cracking temperature, in passing the oil thence to a selective one of a plurality of conversion chambers where conversion of the oil occurs and where residuum forms, in periodically cutting 105 one of the conversion chambers out of the system for cleaning and simultaneously cutting into the system a second conversion chamber, in maintaining a predetermined temperature and superatmospheric pressure 110 on said latter chamber at the time it is cut into the system, by externally heating therein a body of oil prior to cutting said latter chamber into the system. 115

5. An oil conversion process, consisting in 120 heating a stream of oil to a cracking temperature, in delivering the oil to one of enlarged alternative chambers, in diverting the stream of oil from said chamber when substantial coke deposition has occurred there- 125 in to the alternative chamber, and in heating said alternative chamber before diverting the oil stream by heating a body of oil introduced thereto by applying external heat to said alternative chamber.

6. An oil conversion process, consisting in 130

continuously advancing a restricted stream of oil through a heating zone to be subjected to a cracking temperature, in transferring the moving stream of heated hydrocarbon material to one of alternative enlarged chambers, in diverting the continuously moving stream of heated hydrocarbons without any substantial interruption in its flow through the heating zone from said chamber 5 when substantial carbon residue has accumulated therein to the alternate chamber, in maintaining a superatmospheric pressure on the oil undergoing conversion, in subjecting vapors generated from the oil converted in either of said chambers to reflux condensation, in re-cracking the reflux condensate by admitting the same to the heating zone, and in preventing the return of carbon containing residue from either chamber to the stream of oil in the heating zone. 15

CARBON P. DUBBS.
